UNITED STATES PATENT OFFICE.

JACOB FELBEL, OF NEW YORK, N. Y., ASSIGNOR TO UNION TYPEWRITER COMPANY, OF JERSEY CITY, NEW JERSEY, A CORPORATION OF NEW JERSEY.

TYPE-WRITING MACHINE.

No. 880,875.

Specification of Letters Patent.

Patented Feb. 25, 1908.

Application filed December 28, 1904. Serial No. 238,588.

To all whom it may concern:

Be it known that I, JACOB FELBEL, citizen of the United States, and resident of the borough of Manhattan, city of New York, in 5 the county of New York and State of New York, have invented certain new and useful Improvements in Type-Writing Machines, of which the following is a specification.

My invention relates to typewriting machines and more particularly to the ribbon mechanism of such machines.

In visible writing machines employing a ribbon, it is common to arrange the latter so that normally it does not cover the printing 15 point, and to provide means to cause said ribbon to move automatically to cover the printing point at each printing operation and thereafter to return to normal position.

One object of my invention is to provide 20 a construction wherein a ribbon having a plurality of fields of different characteristics may at each printing operation be moved to cover the printing point with any desired field of the said ribbon.

Another object is to provide means to dispense at will with the crosswise feed of the 25 ribbon in that class of machines employing a ribbon vibrator and wherein the ribbon has a crosswise and a lengthwise feed.

A further object is to provide means to 30 enable a parti-color ribbon to be employed in the last-named class of machines.

Another object is to dispense at will, in a 35 machine of the last-named class, with the vibratory movement of the ribbon.

In accordance with my invention, in a machine provided with means for feeding the ribbon lengthwise and crosswise and for moving it to and away from the printing 40 point at each key depression, I have provided mechanism whereby first, a plain one-color ribbon may be used and fed lengthwise and crosswise and also vibrated to and from the printing point; secondly, whereby 45 a two-color ribbon may be used and fed longitudinally with either field of color in use at will and vibrated to and from the printing point without crosswise feed of the ribbon; thirdly, whereby the said two-color 50 ribbon may not only be fed lengthwise and to and from the printing point but also crosswise during such vibratory movement, so that both fields of the ribbon will be automatically utilized alternately, thus produc-

ing variegated impressions; fourthly, means 55 whereby both the vibratory and crosswise feed motions will be eliminated so that the machine may be used for mimeograph or duplicating work, in which kind of work, as is well known, the inking ribbon is temporarily thrown out of use and the types made to strike directly upon the mimeograph paper; fifthly, means whereby a plain one-color ribbon may be used in at least two longitudinal lines at will so as to more thoroughly 60 exhaust the ink of the ribbon.

Other objects will subsequently appear.

To the above ends the invention consists in the features of construction, arrangements of parts and combinations of devices, to be 70 hereinafter more fully described and particularly pointed out in the appended claims.

In the accompanying drawings, Figure 1 is a vertical, front to rear sectional view, taken about centrally, of one form of typewriting machine embodying my invention. Fig. 2 is a fragmentary front elevation showing the upper portion of the machine. Fig. 3 is a rear view taken on a plane represented by the line *x* in Fig. 1, various parts being 75 omitted. Fig. 4 is a fragmentary top plan view showing parts of the ribbon mechanism. Figs. 5 and 6 are enlarged top plan views similar to Fig. 4, but showing various parts in different positions from those in 80 Fig. 4, in which they appear in said Fig. 4. Fig. 7 is a view in miniature of a composite ribbon.

My invention is shown as embodied in a Monarch typewriting machine, but it is to be understood that it may be adapted to 90 other forms of writing machines.

In the drawings, 1 indicates the base of the machine supporting corner posts 2 which in turn sustain a top plate 3. Key levers 4, each provided with a key cap 5 and a re-storing spring 6, are fulcrumed near their rear ends on a fulcrum plate 7. Pivoted at 8 to each key lever is a sub-lever 9 formed at its lower end with a slot 10 which embraces a fixed fulcrum rod 11, the latter passing from side to side of the machine beneath the series of key levers. A connecting link 12 is pivotally connected at 13 with the upper end of each sub-lever, and the forward end of said connecting link is pivoted at 14 100 to a type bar 15, which latter is one of a segmentally arranged series, each type bar whereof may be seated in a radial slot 16.

formed in a segmental type bar support 17. The heel of each type bar may be perforated to permit of the passage of a segmental pivot wire 18 contained in a groove cut in the top of the segmental type bar support 17. Instead of this mode of pivoting the type bars on a fulcrum wire, the type bars may be provided with separate hangers and pivots. The type bars are normally supported at their outer ends by a type rest 19 and each bar is provided with a type block 20, the types whereof are adapted to co-operate with a platen 21 when said type bar is suitably actuated.

15 The platen 21 is mounted in a carriage 22, the latter being guided and supported by anti-friction balls 23 which are seated in grooved rails 24 on the carriage and in oppositely grooved rails 25 fixedly secured to brackets 25^a secured to the top plate of the machine. The carriage 22 is provided with a feed rack 26 which normally meshes with a pinion 27, the latter being operatively connected with an escapement wheel 28.

20 Adapted to co-operate with the escapement wheel are feed dogs 29 which are mounted on the upright arm 30 of a pivoted dog rocker 31, the forwardly extending arm 32 whereof is connected with the upper end of

25 a connecting rod 33, which latter at its lower end is connected with a rearwardly extending arm 34 of a universal bar frame 35 pivoted in the base of the machine at 36 and provided with a restoring spring 37. The

30 frame 35 carries a universal bar 38 which extends from side to side of the machine beneath the spacing levers (not shown) and the series of key levers 4, and is adapted to be actuated by said levers when the latter are depressed, as happens during each printing or spacing operation. The carriage 21 is connected by a strap 39 with a spring drum 40 which constantly tends to draw the carriage to the left so that when the universal bar 38 is actuated, the escapement mechanism just described is caused to be operated in a well-known manner and thereby to permit of letter space movements of the carriage.

35 40 Ribbon spools 41, arranged above the top plate at each side of the machine and forwardly of the platen, receive a ribbon 42 which, as herein shown, is divided longitudinally into fields *a* and *b* of different characteristics; that is to say, the field *a* may be of one color, such as black, and the field *b* may be of another and different color, such as red or the field *a* may be copying ribbon and the field *b* record ribbon, for example. The

45 50 ribbon 42 may be fed longitudinally from either spool to the other by any suitable means.

A ribbon feed mechanism is illustrated in the drawings, which, generally speaking, is similar to that employed in the Monarch

typewriting machine and which is explained in United States Patent to Jacob Felbel & Carl Gabrielson, No. 703,339, dated June 24, 1902.

Each ribbon spool 41 is carried by an upright shaft 43 which rotates in a fixed bearing 44 and has secured to its lower end a small beveled gear 45. The gear 45 meshes with a beveled pinion 46 secured to the forward end of a horizontal shaft 47, which shaft carries at its rear end a beveled pinion 48 which is adapted to mesh with a beveled pinion 49 mounted on a driving shaft 50. Rotary movement is transmitted to the shaft 50 by beveled pinions 51 and 52, the pinion 51 being operatively connected with the driving shaft and the pinion 52 with the spring drum 40. It will be understood that both ribbon spools are provided with similar gear trains which are adapted to be actuated from driving pinions 49 on the driving shaft 50. As explained in the above cited patent, the driving shaft 50 is capable of longitudinal movement, and it is further to be understood that the longitudinal position of said shaft determines which driving pinion 49 will be in mesh with its co-operating pinion 48, and which ribbon spool will be turned to wind the ribbon thereon.

Midway between the ribbon spools, the ribbon 42 is threaded through a ribbon vibrator or carrier 53 which is guided and supported in the upright arms 54 of the supporting bracket 55 secured by screws 56 to the top plate of the machine. The lower end of the vibrator or carrier 53 is bifurcated and carries a pin 57 which is embraced by the slotted forward end of an operating lever 58 pivoted at 59 in a lug 60 depending from the top plate. The rear arm of the operating lever 58 is formed with a horizontal slot 61 which receives a pin or stud 62 secured at the top of a vertically arranged link 63. The link 63 is provided near its upper end with a downwardly bent arm 64, and at its lower end said link is pivoted at 65 in a connecting member 66 which in turn is pivotally connected at 67 with the arm 34 of the universal bar frame. The link 63 is adapted to be swung about the pivot 67 in order to cause the stud 62 to move longitudinally of the slot 61 so as to engage the operating lever 58 at varying distances from its fulcrum 59 and thereby to vary the throw of the ribbon carrier or vibrator 53. As herein illustrated, the means employed to swing the link 63 in order to vary the throw of the ribbon comprises essentially an eccentric controller designated as a whole by the numeral 68, which is slidably mounted upon the driving shaft 50, and which is normally adapted to co-operate with the strap formed by the link 63 and its bent arm 64, as best appears in Figs. 1, 3 and 4.

The mechanism thus far described does

not differ essentially, except as hereinafter specified, from that of the Monarch type-writing machine.

Assuming that a one-color ribbon is in use and it be desired to employ a two-color ribbon, the latter may be substituted either by removing from its spools the one-color ribbon and replacing said ribbon with the two-color ribbon, or by bodily removing both the one-color ribbon and its spools from the machine and replacing them by another set of spools carrying a two-color ribbon, or otherwise. The eccentric device hitherto employed, is an eccentric with a broad working face and which is fixedly attached to the driving or power shaft 50. The eccentric controller 68 differs somewhat from the former eccentric controller and comprises a comparatively narrow eccentric working face 69, a tapered portion 70 and a sleeve portion 71, which latter is formed with a circumferential groove or depression 72. A screw 73 passes through the sleeve portion 71 of the eccentric member 68 and enters an elongated slot or groove 74 in the driving shaft 50. The eccentric member 68 is thereby slidably connected with the driving shaft 50 and is caused to rotate with said shaft, but may be moved longitudinally of said shaft without affecting the latter. The driving shaft 50 may also be moved longitudinally without affecting the member 68. The longitudinal movement of the eccentric member 68 is controlled by a positioning or switching member or slide 75 which comprises first a vertically disposed arm 76 terminating at the top in a perforated collar portion 77 and at the lower end in a fork 78 which partially surrounds the depression 72 of the member 68, and second, two right-angled arms 79 and 80 which are connected with said arm 76 at opposite sides of the latter and somewhat below the collar portion 77 and extend horizontally and to the right of said arm 76, as viewed from the rear of the machine. The forward arm 79 is formed with a shoulder 81 and terminates in an inwardly projecting lug or hook 82. The rear arm 80, which is somewhat shorter than the arm 79, is formed with a shoulder 83 and terminates in an inwardly projecting lug or hook 84. A pull and push rod 85 has its inner end fixedly secured in the collar portion 77 of the positioning member or slide 75, and bears in the flange of the top plate, passing through the latter and terminating at the outer end exteriorly of the machine in a finger button 86. The rod 85 is formed with notches 87, 88 and 89 with which a locking spring 90 is adapted to engage, said locking spring being secured to the under side of the top plate 3 by a screw 91. The pull and push rod 85 also has a bearing in a lug 92 depending from the top plate, which lug serves also as one of the bearings 65 of the driving shaft 50. Forward of the link

63 is a link 93, the upper end of which is provided with a pin or stud 94 which is adapted to enter the elongated slot 61 near its forward end and between the pivot or fulcrum 59 and the stud 62 of the link 63. For most work, however, the stud 94 stands normally out of engagement with the slotted operating lever 58. The lower end of the link 93 is pivoted at 95 in a connecting member 96 which in turn is pivoted at 97 to the arm 34 of the universal bar frame, these pivots like the pivots 65 and 67 being at right angles to each other. As viewed in Fig. 3, the link 93 is prevented from turning to the right about its pivot 95 by an upstanding stop 98 which is integral with the connecting member 96. A small spiral spring 99 is attached at one end to the link 93 and at the other end to a pin 100 depending from the under side of the top plate, and said spring constantly tends to draw the link 93 rearwardly about its pivot 67.

When positioned as shown in Figs. 1, 3 and 4, the mechanism is adapted to give a variable transverse feed to the ribbon, the stud 62 under the control of the eccentric face 69 moving towards and away from the fulcrum 59 and thereby varying the distance the ribbon moves upward at each printing operation. The ribbon is fed longitudinally at the same time so that the impressions of the types make a serpentine or wavy path lengthwise of the ribbon and curving from side to side thereof. When, therefore, the ribbon 42 has been substituted for the usual and ordinary ribbon it is necessary in ordinary writing to prevent the variable movement of the ribbon vibrator, as otherwise some impressions would be made on the paper from the field *a* of the ribbon 42 others from the field *b* of said ribbon and others from both fields. As indicated in Fig. 3 the pull and push rod 85, when the ribbon is adapted to feed cross wise automatically, is in its inward position with the locking spring 90 in engagement with the notch 87 of said rod. In order to prevent variable throw of the ribbon vibrator, the rod 85 is pulled outward, or toward the left as viewed in Fig. 3, by means of the finger button 86, until the locking spring 90 engages with the second notch 88. This leftward movement of the rod 85 carries with it the positioning member 75 attached to the inner end of said rod, and the connection between the fork 78 of said positioning member and the sleeve portion 71 of the eccentric member 68 causes said eccentric member to likewise move to the left (as viewed in Fig. 3), until the eccentric face 69 has passed out of engagement with the link 63. As soon as this disengagement occurs the spring 99 will pull the link 63 back towards the rear end of the slot 61. The leftward movement above referred to of the positioning member 75 causes the arms 79 and 80 of said member to assume the

position shown in Fig. 5, wherein, it will be noted, the inner face of the lug 82 is in contact with the upper portion of the link 93 and the inner face of the lug 84 is in contact 5 with the upper portion of the link 63.

When the locking spring is engaged with the second notch 88 of the rod 85, and the parts connected with said rod (that is, the 10 positioning member 75 and the eccentric or controlling member 68) have assumed the positions above described, the pin 62 of the link 63 will be always maintained at the rear end of the slot 61 in the operating lever 58 by the spring 99. The result is that the 15 ribbon vibrator 53 will be operated by said lever 58 to lift the ribbon at each printing operation to a position relative to the printing line which is unvarying. The parts are so adjusted that this unvarying movement 20 of the ribbon vibrator will always bring the printing field *a* of the ribbon 42 into position to receive the impressions of the types. The path of the type impressions will then be in a straight line extending longitudinally 25 of the fields *a* of the ribbon.

If it be desired to print from the lower field *b* of the ribbon 42, the rod 85 is pulled out still further until the locking spring 90 engages with the third and last notch 89 in 30 said rod. This draws the positioning member 75 still further leftward, as viewed from the rear of the machine, with the result that the link 63 is caused to swing to the left about its pivot 65 under the influence of the 35 lug 84 of the arm 80, and the link 93 is swung leftward about its pivot 95 by the lug 82 of the arm 79. The parts will now be in the 40 positions illustrated in Fig. 6, wherein it will be noted that the stud 62 has been withdrawn from the slot 61; thereby disconnecting the link 63 from the operating lever 58; and the stud 94 has been brought into engagement with the slot 61, thereby connecting 45 the link 93 with the operating lever 58. The link 93 is secured to the universal bar frame somewhat nearer the center of motion 50 of said frame than is the lug 63, and consequently the downward movement of said link 93 at each printing operation is somewhat less than is the downward movement 55 of the link 63. The link 93, however, acts upon the operating lever 58 so much nearer the fulcrum 59 than does the link 63, when the latter is connected with said operating 60 lever in the manner illustrated in Fig. 5, that the said operating lever is moved a greater distance when it is connected with the link 93, as illustrated in Fig. 6. The result is 65 that the ribbon vibrator is lifted to a greater height in the latter case, and the parts are so adjusted as to bring the field *b* of the ribbon 42 into printing position at each printing operation. The throw of the lever 58 under the influence of the link 93 does not vary and the path of the type impressions

will be in a straight line running longitudinally of the field *b* of the ribbon.

If it be desired to again position the parts to cause the ribbon to feed crosswise automatically, the rod 85 is pushed in until the locking spring 90 engages with the notch 87. As the rod is pushed in, the tapered or cam portion 70 of the eccentric member will effect an easy and certain entrance into the space 70 between the link 63 and its bent arm 64, and 75 will thereby insure that the eccentric face 69 will again engage with the strap of the link 63. This return movement of the rod 85 also causes the shoulder 81 of the forward arm 79 of the positioning member 75 to 80 swing the link 93 back, towards the right hand as viewed in Fig. 3, about the pivot 95, and causes the shoulder 83 of the rear arm 80 to swing the link 63 to the right about its pivot 65. The parts are thereby restored to 85 the positions illustrated in Figs. 3 and 4. The friction devices, comprising the spring 90 in cooperation with the notches or depressions in the rod 85, may be replaced by other devices for maintaining the switching mechanism in one or another of its positions as 90 desired.

As previously stated, if the printing devices be operated with the parts positioned as last described, some of the type impressions, because of the variable throw of the ribbon vibrator, will be made on the field *a*, others on the field *b*, and others partially on one field and partially on the other. If the fields *a* and *b* of the ribbon be of different 100 colors, say, for example, red and black, a vari-colored effect will be obtained, which result may be desirable in ornamental type-writing or the like. For ordinary forms of work, however, the ribbon 42 should be replaced by a one-color ribbon when the parts are to be operated in the last described 105 relation.

In preparing stencils for mimeograph work, it is desirable to maintain the ribbon 110 at all times out of the printing field. My invention provides a way to accomplish this result; namely, by dispensing with the forward link 93. When this is done and the positioning member is actuated so as to disengage the link 63 from the operating lever, the latter is entirely disconnected from the universal bar and printing mechanisms and will remain motionless throughout the operation of the machine, and the ribbon vibrator 115 or carrier will maintain the ribbon below the printing or writing line on the platen. The term ribbon vibrator or carrier as used throughout the specification and claims is intended to cover any device for moving the 120 ribbon to and from the printing point during the operations of printing keys.

From the foregoing and from the drawings, it will be seen that the mechanism herein shown and described is capable of a vari- 125

ety of uses, some of which may be stated as follows:—When the link 63 and the crosswise feed mechanism are in operative relation to the ribbon vibrator, a plain one-color 5 ribbon may be used, and as the keys are operated, the ribbon will be fed not only longitudinally from one spool to the other but also progressively crosswise so as to utilize practically all of the surface of the 10 ribbon, while at the same time and by the same means the ribbon vibrator is thrown to a normal position so as to cover the printing point to receive the actuated type, and then after the impression said vibrator is permitted 15 to return to its normal lower or rear-most position. But when the described parts are still in operative relation to the pivoted carrier, a two-color ribbon may be used instead of a one-color ribbon and the 20 types will print from both stripes of the ribbon, the impressions gradually changing in color in accordance with the progressively varying movements of the vibrator, due to the action of the strap and eccentric forming 25 part of the crosswise feed mechanism. Ordinarily a two-color ribbon would be used, with the said devices in working position, only where it may be desired to do variegated or fancy colored work. Where I speak 30 of the two-color ribbon, I do not wish to be limited always thereto, because for doing certain fancy work, the ribbon may be provided with more than two different colors.

When it may not be desired to utilize the 35 ribbon progressively transversely of its length, the eccentric is switched out of operative relation with the strap of the link 63, but said link may be left in engagement in the normal or rearmost position with the vibrator operating lever and by its reciprocations move the ribbon vibrator through said lever a fixed or predetermined distance. At this time there may be in the machine either a one-color ribbon or a two-color ribbon. If a 40 one-color ribbon is in use, it will be utilized along the upper half or portion thereof, since the link 63 is adapted to throw the ribbon vibrator and ribbon the minimum distance from the normal position of the vibrator. But 45 the mechanism is such that when the upper portion of said one-color ribbon has been sufficiently used up the link 63 may be shifted out of connection with the operating lever and the link 93 switched into connection 50 with said lever; thereafter during the normal operation of the machine, the ribbon vibrator and the ribbon will be caused to move by said link 93 a greater distance than by the link 63 and hence the lower half or 55 portion of the ribbon will be moved to cover the printing point and will be utilized by the types. Thus the invention is adapted for getting the maximum amount of ink out of the ribbon of one color in a front strike machine by means which may be conveniently 60

operated exteriorly of the machine so as to cause the different portions of the ribbon to be thrown to the printing point and back again as may be desired.

It will be understood of course that while 70 the parts are in the positions last mentioned, a two-color ribbon may be substituted for the one-color ribbon and if this two-color ribbon be, say, black and red, the black or upper portion will be struck by the types 75 when the link 63 is connected with the vibrator, and said ribbon will be moved so that its lower or red portion will be struck by the types when the link 93 is connected with the vibrator and the link 63 disconnected therefrom, it having been explained heretofore 80 that because of the relative positions of said links and the pivot or fulcrum of the operating lever, said lever is thrown different distances from a normal position. By a normal position I mean that by operating either 85 of said devices, the ribbon vibrator and ribbon start practically always from the same place, and after moving to the printing point, they return always to substantially 90 the same place from which they started so that the writing of the last letter is uncovered or exposed to the view of the operator.

The mechanism shown and described may be used with the novel form of composite 95 ribbon illustrated at Fig. 7. From this view it will be seen that said ribbon comprises different sections or parts which may be variously inked so as to provide different colors or different characteristics of links. For example, the middle portion of the ribbon marked *c* may constitute a considerable portion of the ribbon as a whole and may comprise simply one solid color, as black, blue, green, etc., copying or non-copying, according 100 to the needs of the operator, it being understood that the major part of the work done with the typewriting machine is with a ribbon of one color. Occasionally, or for billing or tabulating purposes, it is desired to 105 use two colors, usually black and red, and it is the custom now when such two-color work is to be done, to remove the one-color ribbon from the machine and substitute therefor the desired two-color ribbon. Then, when the 110 end of the two-color work has been reached, the operator must remove the two-color ribbon and replace in the machine the one-color ribbon. From the ribbon shown at Fig. 7, it will be noted that I have provided at each 115 end portion of the ribbon two different stripes or fields of color, one of which may be black, as at *a*, and the other red, as at *b*. Between each end of the one-color middle portion *c* and the two-color portions *a*, *b*, I 120 prefer to leave the ribbon blank or white, as at *d*, or treat it so that no impression can be taken therefrom.

In the use of such a composite ribbon, it 125 will be seen that if an operator is doing work 130

with the middle one-color portion of the ribbon and the end of such portion runs off of the paying-off spool, she will be quickly apprised of that fact by reason of the intermediate white or non-printing portion of the ribbon coming to view, and if the operator has not finished with the one-color portion of the ribbon, she may reverse the lengthwise feed by hand in any of the known ways and continue to use such portion of the ribbon until she shall have occasion to use the two-color portion of the ribbon. When that time comes, the operator has simply to turn the ribbon spools by hand until the two-color portion of the ribbon has registered with the printing point and she may then proceed to utilize either of said colors at will by operating the ribbon shifting mechanism according to her requirements. If the two-color portion of the ribbon shall pay off entirely from its spool before the operator has finished with the two-color work, the ribbon may be reversed by hand or automatically and this portion continued in use until such time as the one-color ribbon may again be needed. By placing the two-color portions at each end of the ribbon as a whole, a saving of time is effected in going from the one-color, to the two-color, depending upon the quantity of one-color ribbon on either the paying-off spool or the taking-on spool. But, of course, if desired, the two-colored portion may be at one end only of the ribbon or it may be otherwise located in the length of the ribbon. Again, one end of the ribbon may consist of two colors, as black and red, and the other, copying or non-copying ribbon, both in the same color or different colors.

It will be understood that with one such ribbon as shown in Fig. 7 in use in the machine, the operator may, without changing the spools or detaching the ribbon, be able to do a variety of work and in a way much more convenient than heretofore. The composite ribbon shown in Fig. 7 is reserved for a separate application.

Various changes in the relations, arrangements and construction of the parts may be effected and parts of my invention may be used without other parts, all without departing from the spirit and scope of the invention.

What I claim as new and desire to secure by Letters Patent, is:

1. In a typewriting machine, the combination of key levers, a ribbon vibrator, means operable by the key levers and normally connected with said vibrator for operating it, and means also operable by the key levers but normally disconnected from said vibrator; said last mentioned means being also adapted to operate the vibrator when connected therewith.

2. In a typewriting machine, the combination of a ribbon vibrator, vibrating means normally in operative engagement therewith,

vibrating means normally out of engagement therewith, and means for disengaging the first mentioned vibrating means from and engaging the second mentioned vibrating means with said vibrator.

3. In a typewriting machine, the combination of key levers, a ribbon vibrator, actuating means operable by the key levers and normally in operative engagement with said vibrator, other actuating means also operable by the key levers and normally out of engagement with said vibrator, and switch mechanism for connecting the last mentioned means with the ribbon vibrator and for disconnecting the first mentioned means therefrom.

4. In a typewriting machine, the combination of a ribbon vibrator, a key actuated universal bar, and two independent means between said universal bar and said ribbon vibrator, and operable by said universal bar, either of which means is adapted to actuate said vibrator at will.

5. In a typewriting machine, the combination of a ribbon vibrator, printing keys, means operable thereby to throw said vibrator a given distance from a normal position, and other means also operable by the printing keys and adapted to be connected to said vibrator for throwing it a different distance from said position.

6. In a typewriting machine, the combination of a ribbon vibrator, printing keys, means operable thereby for throwing the vibrator a given distance, other means also operable by the printing keys for throwing the vibrator a different distance, and hand actuated means for switching one of said vibrator actuating means out of operative relation with said vibrator and the other into operative relation therewith.

7. In a typewriting machine, the combination of key levers, a ribbon vibrator, means connected therewith for throwing said vibrator a given distance, other means normally disconnected therefrom for throwing said vibrator a different distance, both said means being operable by the key levers and a switching mechanism adapted simultaneously to throw out the normally operative means and throw in the normally inoperative means.

8. In a typewriting machine, the combination of printing keys, a ribbon vibrator adapted to be moved a predetermined distance so that the types will strike along one portion of the ribbon and also adapted to be moved to another predetermined extent so that the types will strike along another portion of said ribbon, and duplex means operable by the printing keys interchangeable at will for so actuating said ribbon vibrator.

9. In a typewriting machine, the combination of printing keys, a ribbon vibrator, a means operable by the printing keys for mov-

ing the vibrator a predetermined distance from a normal position and permitting it to return to such normal position, and a separate means also operable by the printing keys for moving the vibrator a greater distance from said normal position and permitting it to return to said normal position.

10. In a typewriting machine, the combination of printing keys, a ribbon vibrator movable different distances from the normal position, a means operable by the printing keys for moving said vibrator one of said distances, a separate means also operable by the printing keys for moving the vibrator the other of said distances, and hand actuated means for throwing one actuating means out of operative relation to the ribbon vibrator and the other into operative relation therewith.

20. 11. In a typewriting machine, the combination of a ribbon vibrator, a universal bar, sets of devices operable by the universal bar and between said universal bar and said ribbon vibrator, and printing keys for operating said universal bar, one set of said intermediate sets of devices being operative to throw the ribbon vibrator a predetermined distance and another set of said devices being adapted to throw said vibrator a different distance, 30 and said sets of intermediate devices being arranged and adapted to be connected with and disconnected from said vibrator at will in accordance with the extent to which it may be desired to throw the ribbon vibrator.

35. 12. In a typewriting machine, the combination of a ribbon vibrator, a universal bar, printing key levers for operating the same, and a duplex vibrator actuating mechanism, operable by said printing key levers, one part 40 of said duplex mechanism being out of operation when the other part is in operation, both parts of said mechanism being operable by all of the printing key levers.

13. In a typewriting machine, the combination of a ribbon vibrator, a universal bar, printing key levers for actuating said universal bar, and link and lever mechanism between said universal bar and said ribbon vibrator, one of said link and lever elements 50 being single and the other double, and one of said members being normally out of engagement and the other normally in engagement, and means for reversing this condition of the parts, the construction being such that when 55 the reversing means is actuated the link element is positively attached to or detached from the lever element.

14. In a typewriting machine, the combination of a ribbon vibrator, a lever for operating the same, a pair of links for operating said lever alternately, a universal bar connected to said links and capable of operating the same, and printing key levers adapted to 60 actuate said universal bar.

65. 15. In a typewriting machine, the combi-

nation of a ribbon vibrator, a lever having a fixed fulcrum for actuating the same, a vibrating means operative upon said lever at a predetermined distance from its fixed fulcrum, a second vibrating means operative 70 upon said lever at a different predetermined distance from its fixed fulcrum, and means for shifting said operative means alternately into and out of engagement with said lever.

16. In a typewriting machine, the combination of a ribbon vibrator, a lever for operating the same, a key actuated universal bar, and a pair of links connected to and operable by said universal bar, one of said links being adapted to operate upon one part of said 75 lever to throw the vibrator a predetermined distance and the other link being adapted to operate on another part of said lever to throw said vibrator a different distance.

17. In a typewriting machine, the combination of a ribbon vibrator, a lever for operating the same, a key actuated universal bar, a pair of links connected to and operable by said universal bar, one of said links being adapted to operate upon one part of said lever to throw the vibrator a predetermined distance and the other link being adapted to operate on another part of said lever to throw said vibrator a different distance, and hand actuated means for throwing one link 90 into engagement with said lever and the other link out of engagement therewith.

18. In a typewriting machine, the combination of a ribbon vibrator, means for moving it to and from the printing point, means 100 for moving it progressively crosswise during the operation of the printing keys, and means for temporarily disconnecting the means employed for progressively moving the ribbon crosswise and putting the vibrator in control of the means for moving it to and from the printing point.

19. In a typewriting machine, the combination of a ribbon vibrator, means for moving it to and from the printing point, means 110 for giving the ribbon variable cross feed during the operation of the printing keys, means adapted to throw the ribbon vibrator different predetermined distances from the normal position, and means whereby the 115 automatic cross feed mechanism may be switched out of operation, and the other recited mechanism switched into operation.

20. In a typewriting machine, the combination of a ribbon vibrator, means for 120 throwing the same a given distance from the normal position, a separate means for throwing the vibrator a different distance from said normal position, one of said means being inoperative while the other is operative, 125 means adapted to operate the ribbon vibrator varying distances so as to utilize the ribbon progressively crosswise of its surface, and mechanism adapted to either throw out the progressively crosswise feeding means 130

and bring into play alternately the mechanisms for throwing the vibrator different distances from the normal position or throwing out one of said throwing mechanisms and 5 bringing into conjoint operation the other of said vibrator throwing mechanisms and the crosswise feeding mechanism.

21. In a typewriting machine, the combination of a ribbon vibrator, a lever for actuating the same, a link adapted to operate on said lever at progressively increasing and decreasing distances from the fulcrum of said lever, means for moving said link so as to operate on said lever, a separate link normally disconnected from said vibrator but adapted to be connected therewith, and means for throwing out of operative relation the means for moving said first mentioned link progressively to and from the fulcrum 15 of said lever, whereby the said two links are adapted alternately to act on said lever and throw the vibrator different distances so as to operate it at different longitudinal portions of the ribbon.

22. In a typewriting machine, the combination of a ribbon vibrator, a slotted lever connected therewith, a link adapted to move back and forth in the slot of said lever, an eccentric for controlling said movements, a 20 second link also adapted to operate with said lever, and means adapted to disconnect the eccentric from its associated link, also adapted to disconnect said link from said lever and further adapted to connect the second mentioned link with said lever.

23. In a typewriting machine, the combination of a ribbon vibrator, an operating lever therefor, a pivoted link provided with a strap, an eccentric adapted to operate within 40 said strap, means for disengaging said eccentric from said strap, and means carried by said eccentric for insuring re-engagement between said eccentric and said strap.

24. In a typewriting machine, the combination of a ribbon vibrator, a lever for operating the same, a link connected to said lever and carrying a strap, an eccentric for operating said link, means for disengaging said eccentric from said strap, and a cam or 50 wedge carried by said eccentric for insuring re-engagement between said eccentric and said strap.

25. In a typewriting machine, the combination of a ribbon vibrator, a lever provided 55 with a longitudinal slot, a pivoted link, one end of which is movable to and fro in said slot, a spring tending normally to pull said link towards one end of said slot, an eccentric adapted normally to work within a strap 60 carried by said link, and means for disconnecting said eccentric from said strap and permitting the spring to move the link towards one end of the slot.

26. In a typewriting machine, the combination of a ribbon vibrator, a lever provided

with a longitudinal slot, a pivoted link, one end of which is movable to and fro in said slot, a spring tending constantly to pull said link towards one end of said slot, an eccentric adapted normally to work within a strap 70 carried by said link, means for disconnecting said eccentric from said strap and permitting the spring to move the link towards one end of the slot, and a cam or wedge carried by said eccentric for insuring reengagement 75 between said eccentric and said strap.

27. In a typewriting machine, the combination of a ribbon vibrator, an operating lever therefor, a pivoted link provided with a strap, a power shaft, an eccentric slidably 80 mounted on said shaft, means extending exteriorly of the machine for operating said eccentric and adapted to disconnect the same from the said link.

28. In a typewriting machine, the combination of a ribbon vibrator, a lever for operating it, a pivoted link adapted to swing in a direction longitudinal of said lever and detachably connected therewith, a power shaft, means on said shaft connected with said link 85 for swinging it longitudinally of said operating lever, and means extending exteriorly of the machine for actuating said means on said power shaft and disconnecting it from said link.

29. In a typewriting machine, the combination of a ribbon vibrator, a lever for operating it, a universal bar, a link operable by the universal bar and connected therewith to swing longitudinally of said lever, and hand controlled means engageable with said link 90 so as to swing it laterally of said lever and disconnect it therefrom.

30. In a typewriting machine, the combination of a ribbon vibrator, an operating lever therefor, a universal bar, a link having 105 two pivots at right angles with each other, means for moving said link about one of said pivots during the normal operation of the machine, and means for moving said link about the other of said pivots and disconnecting it from said operating lever.

31. In a typewriting machine, the combination of a ribbon vibrator, a slotted operating lever therefor, a universal bar, an operating link pivotally connected thereto so as to swing longitudinally of said lever and also pivotally connected so as to swing laterally of said lever, a strap on said link, an eccentric connected to operate within said strap, a means for withdrawing said eccentric from said strap, a spring for moving said link towards one end of the slot when the eccentric has been withdrawn from said strap, a cam or wedge operatively connected to said eccentric for finding said strap and positively reengaging said eccentric therewith, and means adapted to disengage said eccentric from the strap or reengage said eccentric with the strap.

32. In a typewriting machine, the combination of a ribbon vibrator, a vibrator lever, a link for throwing the vibrator to and from the printing point, a crosswise feed mechanism connected to said link, and hand operated means adapted first to disconnect the crosswise feed mechanism from said vibrator and then to disconnect the link from the vibrator lever. 65
- 5 33. In a typewriting machine, the combination of a ribbon vibrator, independent means for throwing said vibrator different distances, a normally operating automatic crosswise feed mechanism operative in connection with one only of said throwing means, and hand actuated means whereby first the crosswise feed mechanism is rendered inoperative, then one of said vibrator throwing means is rendered inoperative, and finally 70 the other of said vibrator throwing means is rendered operative. 75
- 10 34. In a typewriting machine, the combination of a ribbon vibrator, an operating lever therefor, a pair of actuating links each 15 adapted to be moved transversely of said lever for alternate engagement and disengagement therewith, a normally operating automatic crosswise feed mechanism connected with one of said links, and hand 20 operated means adapted successively to throw out of operation said crosswise feed mechanism and one of said links and to throw into operation the other of said links. 25
- 25 35. In a typewriting machine, the combination of printing keys, a ribbon vibrator, means for throwing it up and down different distances and including a pair of links operable by the printing keys, a slide adapted to disengage one link and engage the 30 other link, and means mounted exteriorly of the machine for operating said slide. 35
- 30 36. In a typewriting machine, the combination of printing keys, a ribbon vibrator, a lever for operating it, a pair of links for 35 alternately operating said lever, said links being operable by the printing keys, a power shaft, a slide provided with a device for controlling said links so as to disengage 40 one and engage the other, and a hand device for operating said slide. 45
- 40 37. In a typewriting machine, the combination of a ribbon vibrator, an operating lever therefor, a pair of links adapted alternately to engage said lever, one of said links having a strap, a power shaft, an eccentric adapted to slide on said shaft, a slide adapted to move said eccentric, devices carried by said slide adapted to control said links, and means for controlling said slide. 55
- 45 38. In a typewriting machine, the combination of a ribbon vibrator, an operating lever, a universal bar, a link connecting said operating lever with said universal bar and operable by the latter, a positioning 60 member, and means for operating said member to disconnect said link from said operating lever. 65
- 5 39. In a typewriting machine, the combination of a ribbon vibrator, an operating lever, a universal bar, a link operable by the universal bar and connected at one end with said universal bar, and at the other by a pin and slot connection with said operating lever, a positioning member, and means for actuating said member to cause it to disconnect 70 said link from said operating lever. 75
- 10 40. In a typewriting machine, the combination of a ribbon vibrator, an operating lever, a universal bar, a link operable by the universal bar and connected at one end to 80 said universal bar and at the other by a pin and slot connection with said operating lever, a positioning member provided with an arm adapted to engage said link, a pull rod connected with said positioning member, and means for actuating said rod to cause the arm of said positioning member to actuate 85 said link, and thereby to break the pin and slot connection between said link and said operating lever. 90
- 15 41. In a typewriting machine, the combination of a ribbon vibrator, means for automatically effecting a variable movement of said vibrator during successive printing operations, and mechanism for disconnecting 95 said ribbon vibrator from said means. 95
- 20 42. In a typewriting machine, the combination of a ribbon vibrator, means for automatically effecting a variable movement of said vibrator during successive printing operations, and mechanism for disconnecting 100 and connecting said ribbon vibrator with said means. 100
- 25 43. In a typewriting machine, the combination of a ribbon vibrator, means for automatically effecting a variable movement of said vibrator during successive printing operations, mechanism for disconnecting 105 said ribbon vibrator and said means, and means for effecting an unvarying movement 110 of said ribbon vibrator during successive printing operations. 110
- 30 44. In a typewriting machine, the combination of a ribbon vibrator, means for automatically effecting a variable movement 115 of said vibrator during successive printing operations, mechanism for disconnecting said ribbon vibrator and said means, means for effecting an unvarying movement of said ribbon vibrator during successive printing 120 operations, and independent means for regulating the unvarying movement of said vibrator. 120
- 35 45. In a typewriting machine, the combination of printing keys, a ribbon vibrator, a plurality of means for actuating said vibrator, said means being operable by the printing keys and being independent of one 125

another, and means for connecting at will one or another of said independent actuating means with said vibrator.

46. In a typewriting machine, the combination of printing keys, a ribbon vibrator, an operating lever, a plurality of means for actuating said lever, said means being operable by the printing keys and being independent of one another, and means for connecting at will one or another of said independent actuating means with said operating lever.

47. In a typewriting machine, the combination of printing keys, a ribbon vibrator, an operating lever, a plurality of means for actuating said lever, said means being operable by the printing keys and being independent of one another, and means for connecting and disconnecting at will one or another of said independent actuating means with said operating lever.

48. In a typewriting machine, the combination of printing keys, a ribbon vibrator, an operating lever, a plurality of means operable by the printing keys for actuating said lever, each of said means being adapted to operate the said lever independently and separately and each being adapted to cause a different extent of movement of said ribbon vibrator.

49. In a typewriting machine, the combination of a ribbon vibrator, an operating lever, a plurality of links for vibrating said lever, means for connecting one or another of said links at will with said operating lever, and means for actuating said links to vibrate said ribbon through different extents of movement.

50. In a typewriting machine, the combination of a ribbon vibrator, an operating lever, a plurality of links, a positioning member for connecting one or another of said links with said operating lever, an universal bar, and connections between said links and said universal bar, said links being operable by said universal bar.

51. In a typewriting machine, the combination of a ribbon vibrator, an operating lever, an universal bar, a plurality of actuating links connected with said universal bar and operable thereby, a positioning member, and means for operating said positioning member to cause one or another of said links to engage with said operating lever as desired.

52. In a typewriting machine, the combination of a ribbon vibrator, an operating lever, a pair of links adapted to engage with said operating lever and vibrate it, means for varying the position of one of said links with relation to said operating lever, means for fixing the relation between said link and said lever, means for disengaging said link from said lever, means for causing an engagement between the second link and said lever, and

means for actuating said links to vibrate said ribbon vibrator.

53. In a typewriting machine, the combination of a ribbon vibrator, an operating lever connected therewith, a universal bar, a pair of links connected with said universal bar and adapted to be connected with said operating lever, an eccentric member for varying the relation between one of said links and said operating lever, and a positioning member which is adapted to disengage said last named link from said eccentric member.

54. In a typewriting machine, the combination of a ribbon vibrator, an operating lever connected therewith, an universal bar, a pair of links connected with said universal bar, and adapted to be connected with said operating lever, an eccentric member for varying the relation between one of said links and said operating lever, and a positioning member which is adapted to disengage said last named link from said eccentric member and thereafter to disconnect said link from said operating lever, and to connect the other link with said operating lever.

55. In a typewriting machine, the combination of a ribbon vibrator, an operating lever connected therewith, an universal bar, a pair of links connected with said universal bar and adapted to be connected with said operating lever, an eccentric member for varying the relation between one of said links and said operating lever, a positioning member and a rod connected with said positioning member and adapted to be moved to different extents and thereby to cause said positioning member to disengage said last named link from said eccentric member, and thereafter to disconnect said link from said operating lever, and to connect the other link with said operating lever.

56. In a typewriting machine, the combination of a ribbon vibrator, an operating lever connected therewith, an universal bar, a pair of links connected with said universal bar and adapted to be connected with said operating lever, an eccentric member for varying the relation between one of said links and said operating lever, a positioning member, and a rod connected with said positioning member and adapted to be moved to different extents, and thereby to cause said positioning member first to disengage said last named link from said eccentric member, second to disconnect said link from said operating lever and third to connect the other link with said operating lever.

57. In a front-strike typewriting machine, the combination of printing devices, a ribbon, means for feeding the ribbon longitudinally, means for automatically feeding the ribbon progressively crosswise for its whole width, means for confining the printing operations to the upper portion of the ribbon,

means for confining the printing operations to the lower portion of the ribbon, and means for bringing into operation at will any one of the three last mentioned means.

5 58. In a typewriting machine, the combination of printing keys, a ribbon vibrator, actuating means normally in operative engagement therewith, other actuating means normally out of engagement therewith, both 10 actuating means being operable by the printing keys, mechanism for disengaging the first mentioned means from and engaging the second mentioned means with said vibrator, and devices for maintaining said mechanism in 15 desired position.

59. In a typewriting machine, the combination of printing keys, a ribbon vibrator, means for throwing it a given distance, other means for throwing it a different distance, 20 both said means being operable by the printing keys, hand actuated means for switching one of said means out of operative relation with said vibrator, and the other into operative relation therewith, and friction devices 25 for maintaining said hand actuated means in desired position.

60. In a typewriting machine, the combination of a ribbon vibrator, means for moving it to and from the printing point, means 30 for automatically moving it progressively crosswise during the operation of the printing keys, means for temporarily disconnecting the means for progressively moving the ribbon crosswise and means for maintaining 35 said disconnecting means in desired position.

61. In a typewriting machine, the combination of a ribbon vibrator, means for moving it to and from the printing point, means for automatically moving it progressively 40 crosswise during the operation of the printing keys, means for temporarily disconnecting the means for progressively moving the ribbon crosswise, friction devices for maintaining 45 said disconnecting means in desired position, said devices comprising a locking spring and a member provided with notches or depressions with which said spring is adapted to engage.

62. In a typewriting machine, the combination of a ribbon carrier, two sets of devices for independently operating said carrier and moving it different distances, and a universal bar to which both sets of the independently operating devices are connected.

55 63. In a typewriting machine, the combination of a ribbon vibrator, an operating lever having a fixed fulcrum; lever actuating means adapted to be set by hand so as to act on the operating lever at different distances 60 from its fulcrum to throw the vibrator so that either the upper or lower portion of the ribbon may be written upon at will.

64. In a sight writing typewriter, the combination of a ribbon guide, a pivoted lever by

which the ribbon guide is moved, a means 65 for imparting movement to said lever having a changeable point of connection therewith, and means for changing said point of connection consisting of a longitudinally movable rod engaging the lever-moving means. 70

65. In a sight typewriting machine, a ribbon guide, means to interpose the ribbon between the type and the platen, actuating means for the interposing means, said actuating means being movable to engage the 75 interposing means at different points to vary the throw thereof and means independent of the operation of the machine, determining the position of the actuating means, and causing the ribbon to be moved to a different 80 printing position relatively to the platen.

66. In a typewriting machine, the combination of a ribbon vibrator, an operating lever connected therewith, a universal bar, a plurality of actuating devices connected with 85 said universal bar and operable thereby, a positioning member, and means for operating said positioning member to cause one or another of said actuating devices to engage with said operating lever as desired. 90

67. In a typewriting machine, the combination of a ribbon vibrator, an operating lever, a pair of actuating devices adapted to engage with said operating lever and vibrate it, means for varying the position of one of 95 said actuating devices with relation to said operating lever, means for fixing the relation between said actuating device and said lever, means for disengaging said actuating device from said lever, means for causing an engagement between the second actuating device and said lever, and means for operating said actuating devices to vibrate the said ribbon vibrator. 100

68. In a typewriting machine, the combination of type operating keys, a universal bar reciprocated by said keys, a ribbon vibrator, a ribbon vibrator lever having a relatively fixed fulcrum, a pair of pins or studs at different distances from the fulcrum of said 110 lever for actuating the same, and means for moving said pins or studs simultaneously to throw one of them out of operative relation to the ribbon vibrator lever and to cause the other to move into operative relation with 115 said lever.

69. In a typewriting machine, the combination of printing keys, a universal bar, a ribbon vibrator, a ribbon vibrator lever, a pair of pins or studs arranged at different 120 distances from the fulcrum of said lever and alternately operative at will, and means connected with the universal bar for communicating the motion of the key-strokes to said pins or studs and said lever. 125

70. In a typewriting machine, the combination of a ribbon vibrator, a ribbon vibrator lever having a relatively fixed fulcrum,

type keys, a universal bar, and connections therefrom to the said vibrator lever, said connections comprising a pair of pins or studs arranged at different distances from the fulcrum of said vibrator lever, and means for simultaneously moving said pins or studs and throwing one into operation and the other out of operation.

71. In a visible writing machine, the combination of printing devices, a ribbon normally removed from the printing point, means for feeding the ribbon longitudinally, means for automatically feeding the ribbon crosswise during its longitudinal movements, and means for at will dispensing with the crosswise feed and causing the printing devices to coöperate with the ribbon in one or another of a plurality of straight substantially parallel paths running lengthwise of the ribbon.

72. In a typewriting machine, the combination of a ribbon vibrator, an operating lever therefor, actuating means for said lever comprising a universal bar frame and a de-

vice mounted thereon and adjustable at will 25 on said operating lever to control the throw of the vibrator, and means manually operative from outside the machine to adjust said device.

73. In a typewriting machine, the combination with a ribbon having a portion divided lengthwise into a plurality of parallel stripes or fields of different characteristics and another portion of uniform character throughout the width of the ribbon, of ribbon 35 vibrating mechanism, and means for controlling said mechanism to enable one or another of the stripes to be used at will or to enable the uniform portion to be used crosswise throughout substantially its entire width. 40

Signed at the borough of Manhattan, city of New York, in the county of New York, and State of New York, this 22d day of December A. D. 1904.

JACOB FELBEL.
